UNITED STATES PATENT OFFICE.

WALDO C. DODGE, OF WINTHROP, MASSACHUSETTS.

SMOKING APPLIANCE.

Application filed January 26, 1926. Serial No. 83,806.

This invention relates to personal smoking appliances, such as pipes, and aims generally to improve such appliances and increase the pleasure and lessen the detrimental effects from using them for smoking purposes.

In the accompanying drawing illustrating a selected embodiment of my invention;

Fig. 1 is a longitudinal sectional view 10 through a smoking appliance illustrated as a straight stem pipe, with my improvements applied thereto,

Fig. 2 is a transverse sectional view taken on the line 2—2 of Fig. 1, and,

Fig. 3 is a perspective view of my improved attachment apart from a pipe.

In the illustrated embodiment of my invention I have shown it as applied to a smoking pipe although the invention is also applicable to other smoking appliances as for instance cigar and cigarette holders. In the illustrated form, a pipe 10 of usual construction comprises the usual bowl 11, stem 12, mouth piece 13 having the usual smoke passage 14 extending longitudinally from the bowl through the stem and mouth piece. According to my invention a passage 15 is drilled or otherwise formed between the bowl and the outer end of the mouth piece, 20 herein in the stem extending transversely from the smoke passage 14 to the outside of the stem, preferably toward the lower side thereof, and in position to be covered by a casing or sleeve-like member 16, formed of any suitable material, as for instance metal, 25 wood, imitation ivory, or hard rubber tapered or otherwise shaped to tightly fit around or engage the stem of the pipe. Preferably the casing 16 is provided with a 30 receptacle 17 constituting a saliva and nicotine trap, adapted, when the attachment is in place, to align with and cover the lower end of the passage 15. A portion of one 35 end of the casing 16, preferably adjacent the trap 17 is grooved at 18 or otherwise formed to provide an inlet for outside air into the trap and hence to the passage way 14 but above any contents of the trap to 40 ventilate the trap or permit escape of any undesirable gases.

In use, the casing or member 17 is fitted over the stem 12 of the pipe or other smoking appliance with the trap 17 covering the

open end of the passage 15. In using the pipe, smoke is drawn in the regular manner directly from the bowl 11 to the mouth of the user. Cool atmospheric air is simultaneously drawn into the passage way 14 through the opening 18 and passage way 15, thereby cooling the stem of the pipe and 55 keeping the mouth of the user cool and pleasant. Liquid accumulations, such as saliva or nicotine which may be deposited in the passage 14, are collected in the trap 17, thereby keeping the bowl 11 and passage 60 65 14 dry and free from excessive moisture.

Advantages of my invention are the comfortable and hygienic manner in which the smoker may use the appliance, as well as the ease and rapidity with which the casing 16 70 may be removed from the stem for cleaning.

Obviously my invention is not restricted to the details of construction shown and described, but is susceptible to various changes in shape and size to accommodate 75 different types of smoking appliances. Also the term sleeve like member is intended to include devices which partially surround the stem as well as devices which completely surround it.

What I claim is:

1. A smoking appliance comprising a stem having a longitudinal smoke passage therethrough and a transverse opening communicating therewith, and having on the 85 stem a trap, an air duct leading from the atmosphere to said trap through the upper side wall thereof to ventilate it and permit the escape of gases therefrom.

2. A smoking appliance comprising a stem 90 having a longitudinal smoke passage and a transverse opening communicating therewith, a sleeve like member formed with a trap in alignment with and covering said opening and also formed with means constituting an air duct for admitting outside air to said passage through the upper part of the trap wall to ventilate the trap above the contents and movable to throw the duct and trap out of operative connection with the transverse opening.

3. A smoking appliance comprising the combination with a stem having a longitudinal smoke passage and a transverse opening communicating therewith, of a member fit- 105 ted to said stem and formed with a depre-

sion constituting a trap and also formed with a longitudinal groove on one end adjacent to and communicating with said trap for admitting outside air to said passage.

5 4. A smoking appliance including a bowl and stem communicating with a mouthpiece, a transverse opening into said stem, and a

sleeve covering said opening, said sleeve being formed with a trap beneath said opening, and having an air duct from the atmosphere to said trap. 10

In testimony whereof, I have signed my name to this specification.

WALDO C. DODGE.
